CLAIM

The ornamental design for a wheel beadlock, as shown and described.

DESCRIPTION

FIG. 1 is a perspective view of a wheel beadlock showing my new design;

FIG. 2 is a front view thereof;

FIG. 3 is a back view thereof;

FIG. 4 is a left-side view thereof;

FIG. 5 is a right-side view thereof;

FIG. 6 is a top view thereof;

FIG. 7 is a bottom view thereof;

FIG. 8 is a back-perspective view thereof; and,

FIG. 9 is a close-up view of one of the holes in the invention. In the drawings the broken line showing of a wheel barrel are included for the purpose of illustrating environmental structure and forms no part of the claimed design.

1 Claim, 7 Drawing Sheets(56)
